UNITED STATES PATENT OFFICE.

JOSEPH GARCIA, OF NEW YORK, N. Y.

MACHINE FOR CLEANSING AND EXTRACTING FIBER.

SPECIFICATION forming part of Letters Patent No. 355,073, dated December 28, 1886.

Application filed May 5, 1886. Serial No. 201,255. (No model.)

To all whom it may concern:

Be it known that I, JOSEPH GARCIA, a citizen of the United States, and a resident of New York, in the county of New York and State of New York, certify that I have invented 5 certain Improvements in Machines for Cleaning and Extracting Fiber, of which the following is a specification.

My invention relates especially to devices 10 employed for cleaning and extracting fiber from fibrous plants, and has for its object the provision of a device simple in construction, cheap in manufacture, adapted to be used without danger of injury or accident, and which will be efficient and rapid in operation.

To attain the desired end my invention consists in the construction and arrangement of parts hereinafter fully set forth.

In the drawings, Figure 1 represents a side 20 view of my machine, and Figs. 2 and 3 are detail views of parts of my machine.

Like letters of reference, wherever they occur, indicate corresponding parts in all the figures.

Referring to the drawings, A represents the 25 bed-plate of my machine, which may be provided with any suitable standards, as a. The wheel B, supported by the bed-plate, revolves in suitable bearings, and is provided with a number of tools—namely, the hacking-combs 30 b, or equivalent picking devices, and the scutching blades or knives b', or equivalent scraping devices—rigidly attached to the periphery of the wheel B, so that each tool is held at a suitable inclination from the direction in which the wheel B revolves, and preferably at an angle with the radius of the wheel that is nearest to it, as is customary in such machines.

Supported by standards rising from the bed-plate A, and placed in front of the wheel B and 40 at the rear of the feed-table A', are the guide or feed rolls C, preferably two in number, and similar removing-rolls, D, preferably three in number, are placed in suitable supports beneath the wheel B, as is clearly shown in the drawings. Also supported beneath the bed-plate A, and placed on each side of the rolls D, under the wheel B, are two concave chutes, E and E', which are urged toward the revolving wheel B by means of the springs e, and 45 limited in such motion by means of the adjust-

able screw-threaded rods e', passing through the diagonal braces a' of the frame-work of my machine, and stop-nuts e', thereon placed, as is indicated in Fig. 1.

Placed beneath the rolls D is the endless 55 apron F, which may be moved along by any suitable means.

The operation of parts is as follows: The wheel B is driven by means of any suitable motive power. A pulley, B', rigidly attached 60 to the shaft of the wheel B, serves to impart motion to the rolls C and D, as indicated. The fibrous material is fed to the machine over the table A' and passes through the rolls C, thus avoiding any danger of injury, which is incident to the former method of feeding by hand. The fibrous plants are automatically urged 65 with elastic pressure against the action of the tools on the periphery of the wheel B, the tools being inclined, to avoid cutting or tearing the useful fibers and clogging of the tools with the useless portions of the leaf or plant, and one end of the plant is thus cleaned while the same is being fed through and held by the rolls C. As soon as the cleaned portion of the 70 plant has passed over the concave chute E it is grasped by the removing-rolls D, which serve to hold the plant, while the remaining portion of the same, when freed from the rolls C, is cleaned by the joint action of the concave chute E' and the tools b and b'. It will be observed 75 that my machine is thus automatic in its operation. The removing-rolls D serve to move the plant-fiber after being cleaned, and place the same upon the endless belt F, or equivalent device, which is adapted to carry it to any suitable place for the purpose of further treatment. The waste, dirt, &c., may be carried 80 away over the top of the concave chute E'. 85

The number of the feed-rolls C or of the removing-rolls D may be increased, if desired.

As it is evident that many slight changes in the construction and relative arrangement of parts might be resorted to without departing from the spirit and scope of my invention, 95 I would have it understood that I do not restrict myself to the particular construction and arrangement of parts shown and described.

I am aware that machines for disintegrating fibers have been hitherto used which have been 100

provided with feeding and removing rolls and one chute bearing against a revolving wheel furnished with tools; but in all such machines, whenever one end of the fiber is fed to the machine and cleaned, the other end is retained, which latter end can only be cleaned (on account of the lack of the second chute with which my machine is furnished) by removing the plant and again feeding the same in a reversed position; whereas by my improvement, before the plant has entirely passed through the feeding-rolls, the cleaned end is caught and retained by the removing-rolls, while the remaining portion of the plant is cleaned through the agency of the revolving wheel in connection with the second chute. I do not therefore claim, broadly, a fiber-disintegrating machine; but what I claim as new, and desire to secure by Letters Patent, is—

1. In a machine for cleaning and extracting fiber, the combination, with feeding-rolls and one concave chute adapted to hold and support the plant while a portion of the same is being cleaned, and with removing-rolls and a second concave chute adapted to hold and support the plant while the remainder of the same is cleaned, of a revolving wheel provided with suitable tools and adapted, in connection with the chutes, for the purpose of cleaning the plant, substantially as set forth.

2. In a machine for cleaning and extracting fiber, the combination, with the wheel B, provided with tools, as set forth, of the feeding-rolls C and chutes E and E', substantially as described.

3. In a machine for cleaning and extracting fiber, the combination, with the wheel B, provided with tools, as set forth, of the removing-rolls D and chutes E and E', substantially as described.

4. In a machine for cleaning and extracting fiber, the combination, with the wheel B, provided with tools, as set forth, of the endless apron A², and of the removing-rolls D and chutes E and E', substantially as shown and described.

5. In a machine for cleaning and extracting fiber, the combination, with the wheel B, provided with tools, as set forth, of the feed-rolls C and the removing-rolls D and chutes E and E', substantially as and for the uses and purpose shown and described.

In testimony of the foregoing specification I do hereby sign the same, in the city, county, and State of New York, this 1st day of May, 55 A. D. 1886.

JOSEPH GARCIA.
